RADIO ANTENNA CONSTRUCTION

Charles A. Upson, Lockport, N. Y., assignor, by
mesne assignments, to General Motors Cor-
poration, a corporation of Delaware

Application March 26, 1936, Serial No. 71,001

6 Claims. (Cl. 250—33)

This invention relates to an antenna for use particularly with radio receiving sets mounted in automobiles or similar vehicles, although many features of the invention may be used also under other conditions.

The provision of a satisfactory antenna for radio receivers in an automobile presents a problem of great difficulty. It was formerly possible to build a reasonably satisfactory antenna in the roof structure of an automobile, but with the recent trend toward making the roof of metal, an antenna in the roof is no longer feasible.

It has also been proposed to use, as a radio antenna, a series of wires supported between the axles of the automobile, or a wire or metal structure supported beneath the running board of the automobile at a substantial distance below it and insulated therefrom. Both of these proposed forms of antenna are unsatisfactory, not only from an electrical standpoint, but also from a purely mechanical standpoint, as they are in an exposed or unprotected position so that they are hit by gravel or the like on the road surface, and become coated with snow and ice in the winter.

An object of the invention is the provision of an improved radio antenna which is highly efficient both electrically and mechanically, which is protected from gravel or flying missiles, and which avoids other defects inherent in previous antennae.

Another object of the invention is the provision of an antenna which is relatively simple, easy, and inexpensive to construct, and which does not present an unsightly appearance.

To these and other ends the invention resides in certain improvements and combinations of parts, all as will be hereinafter more fully described, the novel features being pointed out in the claims at the end of the specification.

In the drawings:

Fig. 1 is a diagram illustrating the electrical principles involved in the antenna;

Fig. 2 is a side view of an automobile equipped with a radio antenna according to a preferred embodiment of the invention;

Fig. 3 is a transverse section through the antenna of the preferred form and associated parts;

Fig. 4 is a bottom plan view of the preferred antenna construction with the bottom layer omitted to show the construction above;

Fig. 5 is a fragmentary longitudinal section substantially on the line 5—5 of Fig. 4;

Fig. 6 is a transverse section similar to Fig. 3 showing a modified form of construction;

Fig. 7 is a plan of the construction shown in Fig. 6, with parts removed to show the construction beneath, and

Fig. 8 is a view similar to Fig. 7 showing still another modification.

The same reference numerals throughout the several views indicate the same parts.

Referring now to the diagram in Fig. 1 of the drawings, the automobile body is indicated at 11 and the ground is shown at 12. For any given strength of radio frequency field in which the automobile is placed a given voltage E_1 may be considered as set up across the capacity C_1 between the car body and the ground. If, now, a metallic member 13, such as the radio antenna hereafter described, be associated with the car body, it is seen that there are two capacities which may be considered as being in parallel with the capacity C_1 , namely, the capacity C_2 between the antenna element 13 and the body 11, and the capacity C_3 between the antenna element 13 and the ground 12. The total voltage E_1 therefore divides into the components E_2 across the capacity C_2 , and E_3 across the capacity C_3 . The sum of the voltage components E_2 and E_3 will equal the total voltage E_1 , and the components E_2 and E_3 will have a relation to each other inversely proportional to the capacities C_2 and C_3 .

If the radio receiver in the automobile is to be operated by the voltage E_2 between the element 13 and the body 11, it is desirable that this voltage E_2 be made as high as possible. To this end, the capacity C_2 between the element 13 and the body 11 should be as low as possible, and the capacity C_3 between the element 13 and the ground should be as high as possible. The antenna of the present invention admirably fulfills these desirable conditions, having low capacity to the automobile body and high capacity to the ground, while at the same time being fully protected not only from mechanical injury, but also from ice, salt slush (now common in cities where salt is used for melting ice on streets) and other factors which would tend to short circuit an antenna in an exposed position.

Referring now to the preferred embodiment shown in Figs. 2 to 5, inclusive, the automobile body, here indicated in general by the numeral 15 and having a chassis or frame 16, has the antenna incorporated in the running board. This running board, instead of being of the conventional metal construction, is mainly of some

insulating or dielectric material, such as wood 17, which may be in a single thick layer, but which is preferably laminated. Because this wood panel 17 is thicker than the conventional steel running board, and because it is desired to maintain the top surface of the running board at the conventional standard height while still using supporting brackets 18 of standard height, it is preferable to notch or recess the panel 17 as shown at 19, wherever the brackets 18 occur.

On the bottom side of the dielectric panel 17 are plates 20 of conducting material, such as sheets of aluminum, copper, or the like. It is to be noted especially that one continuous plate 15 the full length of the running board is preferably not employed, because there would be considerable electrical capacity between such a plate and the metal brackets 18. Instead, a series of sections or separate plates are provided between the 20 respective brackets 18 and also, if desired, between the ends of the running board and the nearest adjacent brackets. The metal antenna plates are of such dimensions that they are spaced edgewise a considerable distance from all 25 of the brackets 18, and also from the closest metal frame members 16 and the metal mudguards 21, such spacing preferably being at least 2 to 3 inches.

Jumpers or connecting wires or strips 22, extending around the ends of the metal brackets 18 and spaced a substantial distance therefrom, are used to connect the various antenna sections 20 electrically to each other. One of these sections is connected, in turn, to one terminal 35 of the radio receiving set indicated diagrammatically at 25, by means of a lead-in wire 26 which is spaced a substantial distance (preferably at least 3 inches) from the closest bracket 18 and which is also jumped around the metal frame member 16, being spaced therefrom as far as reasonably possible. The other terminal of the radio set is connected by a wire 27 to the metal parts of the vehicle frame.

A layer 30 of dielectric material, such as one 45 or more plies of wood, is placed beneath the antenna plates 20 in covering relation thereto. This layer 30 is omitted or cut away at the points where the main panel 17 is recessed for 50 reception of the brackets 18. The space between the dielectric members 17 and 30, beyond the edges of the conducting plates 20, is filled by the strips 31 of waterproof sealing material, such as a rubber composition or the like, so 55 that the antenna members 20 are protected against entrance of moisture at their edges by these strips 31, and are protected on their top and bottom surfaces by the dielectric members 17 and 30 which preferably are sufficiently waterproof or moisture resistant for all practical purposes.

The top surface of the member 17 may be covered by a rubber matting or the like 35. If the antenna members 20 are extended to the extreme outer edge of the running board, as is 60 preferably the case and as shown in Figs. 3 and 4, then the rubber covering 35 is preferably extended around the edge of the members 17 and 30 far enough to completely seal and protect the outer edges of the antenna members. The 65 connecting wires 22 are also completely enclosed and protected in any suitable way, as by running them in suitable grooves in the covering 35, or by stopping the channels 19 short of the extreme outer edge of the running board, leaving 70 at the outer edge a portion of the panel 75

17 of full thickness, along the under side of which the wires 22 may run, and which wires may, like the plates 20, be covered by the bottom covering layer 30.

It is now seen that the antenna is completely 5 enclosed and thus protected mechanically from impacts of stones and the like. Furthermore, it is sealed in a substantially moisture-proof manner, so that it is not affected by ice or salt slush accumulating on the bottom of the running board 10 during winter driving. Moreover it fulfills admirably the desirable electrical conditions, the large flat plates 20 parallel to the ground having a relatively high capacity to the ground, and yet having a relatively low capacity to the 15 automobile body, not only because of their spacing away from all metal parts of the body, but also because they are presented edgewise to these metal parts, rather than flatwise, thus again tending to decrease the capacity. 20

In many or most cases, the antenna acts as a counterpoise rather than as a true aerial, the automobile body itself acting as the aerial. In other cases, however, particularly where the automobile has a metal floor which is relatively 25 low and a running board which is relatively high, the antenna parts 20 may act as a true aerial, the automobile body being the counterpoise. But, in either event, and particularly when the metal plates 20 act as a counterpoise, a very 30 efficient and satisfactory antenna construction results, and the word "antenna" as used in the specification and in the accompanying claims is intended in a broad sense as including a construction which operates either as a counterpoise 35 or as an aerial.

It is further to be noted that the construction above described is preferably used in both running boards, at both sides of the automobile, and not merely in one running board. 40 When the vehicle is thus provided with the preferred type of running board antenna at both sides of the automobile, with both sides connected to the radio receiving set, it is seen that the antenna has practically no directional effect 45 because it is not shielded to any substantial extent from signals coming from any particular direction. Hence it will give satisfactory reception irrespective of the way in which the automobile may be pointed with respect to the broad- 50 casting station.

Since the antenna is entirely enclosed in the running board of the automobile, there are no unsightly or unfamiliar parts exposed to view. Indeed, the external appearance of the automobile is not changed in the least when the 55 antenna of the present construction is used.

In Figs. 6 and 7 of the drawings there is illustrated a modified form of construction. Here, as before, the frame of the vehicle is indicated at 16, and the running board supporting brackets are shown at 18. The main body of the running board, as before, is made up of a panel 17 of dielectric material, preferably of wood, either in a single layer or preferably laminated. Instead of placing metal plates on the bottom of this panel 17, as in the previous embodiment, the present modification of the construction employs a series of wires 40 running longitudinally along the running board in 60 grooves 41 provided in either the upper or the lower surface of the panel 17, the upper surface being preferable. In either event, the space in the grooves surrounding the wires is preferably 65 filled with a waterproof sealing compound, and 70

the entire panel is covered by a strip of rubber or the like 35 cemented to it to protect the antenna wires still further against moisture or mechanical injury. A lead-in wire 42 connects the individual antenna wires 41 to each other and runs transversely through a channel 43 to the radio receiving set.

It is to be noted that the wires 40 are all grouped close to the outer edge of the running board, thus being spaced as far as practicable from the vehicle frame, to reduce the capacity of these wires to the vehicle while at the same time not interfering with good capacity between these wires and the ground.

In Fig. 8 of the drawings is shown still another modification, similar in general to the modification of Figs. 6 and 7, except that here thin flat strips of copper or other metal are used, as indicated at 50, in place of the wires 40. When these strips are relatively thin, it is not necessary to provide channels for them in the dielectric panel 17, but they may merely be placed on the top surface of the panel 17, before the waterproof coating layer 35 is applied. The connecting strip 52 connects the individual strips 50 to each other and it, or a wire connected to it, runs to the radio receiving set. The strips 50, like the wires 40, are all grouped near the outer edge of the running board, to reduce capacity between them and the metal vehicle body.

The modifications illustrated in Figs. 6, 7, and 8 are used just like the preferred embodiment shown in Figs. 3, 4, and 5, and those modifications operate on the same electrical principles, and as before, the same construction is preferably employed in both running boards at opposite sides of the automobile, to reduce the directional effect. In both of these modified constructions, as in the preferred form of construction, the electrical conducting means which forms the antenna has a relatively large effective area, comparable to but less than the area of the running board, and the inner edge of this effective area of the antenna is spaced materially outwardly from the inner edge of the running board structure.

This application is a continuation in part of the copending application of Charles A. Upson, Serial No. 13,288, filed March 27, 1935, for patent on Radio antenna for automobiles.

While certain embodiments of the invention have been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A combined weight supporting step and radio receiving antenna for an automobile, comprising a running board structure projecting laterally from one side of the automobile body, said running board structure including as an integral unit two layers of substantially dielectric material, and electrical conducting means interposed between and enclosed by said two dielectric layers, said electrical conducting means being of large area so as to have relatively great electrical capacity to ground and being spaced materially outwardly from the inner edge of the running board to minimize capacity to the automobile body, said conducting means serving as a radio antenna and one of said layers of dielectric material being constructed and arranged to con-

stitute a platform capable of supporting the weight of persons stepping into and out of the automobile.

2. A radio receiving antenna and load supporting step for an automobile, comprising a running board structure projecting laterally from one side of the automobile body, said running board structure including a series of spaced supporting brackets two layers of substantially dielectric material one of which is directly attached to and bridges the space between said brackets to constitute a weight supporting step, and a sheet of electrical conducting material interposed between and enclosed by said two dielectric layers, said sheet being of relatively large area so as to have relatively great electrical capacity to ground and having an inner edge spaced materially outwardly from the side of said automobile body to minimize capacity to the body, said sheet serving as a radio antenna.

3. An automobile construction comprising, in combination, a frame and body structure, a plurality of brackets projecting laterally from said structure, a running board including a plurality of plies of substantially dielectric material secured to and supported by said brackets, a plurality of metal sheets interposed between plies of said dielectric material, each of said sheets being spaced laterally from said brackets so that said sheets do not overlie the brackets, and conducting means connecting said sheets to each other and to a radio set so that said sheets may serve as a radio antenna.

4. A radio receiving antenna for an automobile, comprising a running board structure projecting laterally from each of two opposite sides of the automobile body, each running board structure consisting of two layers of substantially dielectric material constructed and arranged to provide a self-supporting step and electrical conducting means interposed between and enclosed by said two dielectric layers, said electrical conducting means in each running board structure being of large effective area so as to have relatively great electrical capacity to ground, and means electrically connecting said conducting means in one running board to said conducting means in the other running board and to a radio set so that said conducting means in both running boards may serve conjointly as a receiving antenna substantially unshielded by said automobile body and having little or no directional effect.

5. An assembled unit for attachment to an automobile as a combined running board and radio antenna comprising a series of spaced frame brackets, a main running board member constructed of dielectric material having grooves on its underside to receive said brackets, a signal pick-up on the underside of said member in the space between a pair of said brackets and a cover of dielectric material cooperating with said member to completely enclose the signal pick up element.

6. An assembled unit for attachment to an automobile as a combined running board and radio antenna comprising a series of spaced attachment brackets, a main weight supporting platform spanning the space between said brackets and being constructed of dielectric material, a signal pick-up element bearing against one face of said platform and a cover of dielectric material cooperating with the platform to completely enclose said pick-up element.

CHARLES A. UPSON.
